Primary Examiner — John Windmuller*Assistant Examiner* — John R Yeh(74) *Attorney, Agent, or Firm* — Howard and Howard Attorneys PLLC(57) **CLAIM**

The ornamental design for an antenna, as substantially shown and described.

DESCRIPTION

FIG. 1 is a front elevation view of an antenna according to the present invention;

FIG. 2 is a rear elevation view thereof; and,

FIG. 3 is front elevation view of the antenna within an environment.

All elements of the claimed design are flat and coplanar. The broken lines in FIG. 3 illustrate environment and form no part of the claimed design.

1 Claim, 1 Drawing Sheet(56)
